UNITED STATES PATENT OFFICE.

JAMES CAMPBELL, OF ST. LOUIS, MISSOURI, ASSIGNOR TO ST. LOUIS FELLING MACHINE COMPANY, OF ST. LOUIS, MISSOURI, A CORPORATION OF MISSOURI.

METHOD OF MAKING CYLINDER-RINGS.

1,215,775.

Specification of Letters Patent. Patented Feb. 13, 1917.

Application filed July 13, 1916. Serial No. 109,156.

To all whom it may concern:

Be it known that I, JAMES CAMPBELL, a citizen of the United States, residing at St. Louis, in the State of Missouri, have invented certain new and useful Improvements in Methods of Making Cylinder-Rings, of which the following is a specification.

This invention relates to improvements in the method of manufacturing split rings, and more particularly to a method of forming the inside member of a two-piece cylinder packing ring, the periphery of which must be accurately ground to size.

15 One of the objects of my invention is to provide a method for forming an eccentrically ground split ring from a strip of metal.

Another object of my invention is to provide a rapid and inexpensive method of grinding a plurality of split rings to proper size.

A still further object of the invention is to provide a method of forming from a long strip of metal a plurality of accurately ground split rings, all being ground simultaneously.

Still other and further objects will become apparent to those skilled in the art from a consideration of the following description and drawing, wherein:

Figure 1 is a side elevation of a mandrel such as may be employed for carrying out my invention with a strip of metal spirally wound thereon, one end being broken away to illustrate the cap attachment for the end of the mandrel used when an eccentric ring is desired.

Fig. 2 is an end elevation of the device shown in Fig. 1, the end cap being removed.

Fig. 3 is a similar view from the end.

Fig. 4 is an end view with the eccentric grinding cap in place, and;

Fig. 5 is a perspective view of a finished ring.

For the purpose of illustrating my improved method of forming split rings I have shown in the drawings a simple construction which may be utilized and consisting 50 of a cylindrical accurately formed drum or mandrel 10 having reduced end portions 11, 12, provided with lathe centers 13 and 14, respectively.

The end of the mandrel 10 adjacent the 55 reduced portion 11 is provided with a slot

15 adapted to receive one end 16 of the strip from which the rings are to be formed. In order to rigidly secure this end 16 of the strip in position within the slot 15, I have provided a radially extending set screw 17 which takes through from the periphery of the mandrel into the slot.

A long metal strip of a width equal to the desired width of the completed ring is secured at one end 16 within the slot 15, as 60 above described and is then wound spirally about the mandrel 10 as indicated in Fig. 1.

The spiral is wound tight so that the surfaces of the convolutions are in close contact with each other, thus forming a continuous 70 tube or shell surrounding the mandrel 10. The opposite end of the strip is then secured under a clamping stud 18, taking into the opposite end of the mandrel.

The spirally formed shell is now ready 75 for grinding to the desired size, and if the exterior of the ring is to be concentric with the interior surface, the mandrel may be set in a lathe or grinding machine, using the centers 13 and 14 upon which the mandrel 80 was mounted when it was initially formed with its cylindrical surface. On the other hand, if the periphery of the rings, when completed, are to be eccentric to the inner surface I have found that a convenient way

85 to provide offset centers upon which to grind the shell is to secure on each end of the reduced portions 11 and 12 of the mandrel a pair of caps, as 19, the inner diameter of 90 which is formed to make tight fit with the reduced ends 11 and 12 of the mandrel and the outer ends of which are provided with lathe centers 20, slightly offset from the axis 95 of the cap. To prevent rotation of the mandrel with respect to the cap I have formed an opening 21 in the end of each end of the mandrel for registry with the holes 22 of the cap and into which projects a stud 23.

Different sets of caps may be provided with 100 their lathe centers having different degrees of eccentricity depending upon the degree of eccentricity on which the peripheries of the rings are to be formed.

The next operation, after having mounted the mandrel in the centers of the lathe or 105 grinding machine, is to grind the periphery or the tubular shell to the required diameter.

I then secure or clamp the shell by suitable means and saw-cut through each convolution of the coil on a line parallel with 110

the axis of the drum as indicated by the dotted line 25 in Fig. 1. This separates the spiral into a plurality of rings, such as indicated at 26, in Fig. 5.

5 By means of this method I am able to form a large number of perfectly shaped expanding rings by one set of operations, the rings being accurately formed as to size and uniform as to expansibility and other qualities.

10 Whereas I have illustrated simple apparatus by means of which my method may be carried out, it is obvious that various changes may be made therein without departing from the spirit and scope of the following claims.

15 Having described my invention, what I claim is:—

1. The method of manufacturing split 20 rings which consists in securing one end of a metal strip to a round mandrel, winding the strip spirally around the mandrel, securing its opposite end to prevent unwinding of the strip, forming the periphery of the spirally wound strip to the desired shape and cutting the coiled strip on a line parallel to the axis, thereby separating the same into a plurality of split rings.

25 2. The method of manufacturing split 30 rings which consists in securing one end of a metal strip to a round mandrel, winding the strip spirally around the mandrel, with the convolutions in close contact, one with another, securing the opposite end to the

mandrel, grinding the periphery of the 35 coiled strip to the desired size, and subsequently cutting the coils to separate them into a plurality of rings.

3. The method of manufacturing split 40 rings which consists in winding a strip of metal spirally upon a round mandrel, securing the opposite ends to prevent unwinding of the strip, grinding the periphery of the strip to the desired size, and then transversely saw-cutting the wound convolutions 45 to separate the same into a plurality of split rings.

4. The method of manufacturing expandable split packing rings which consists in securing one end of a metal strip of rectangular cross section to a round mandrel, winding the strip under tension spirally around the mandrel with the convolutions in close contact, one with another, securing the opposite end to the mandrel to prevent uncoiling of the strip, mounting the mandrel eccentrically and grinding the periphery of the coiled strip to the desired size, and subsequently saw-cutting the wound convolutions to separate the same into a plurality of 55 expandable split packing rings.

50 In testimony whereof I hereunto set my hand in the presence of two subscribing witnesses.

55 JAMES CAMPBELL.
